[57] CLAIM

The ornamental design for a transportable cart, as
shown and described.

DESCRIPTION

FIG. 1 is a front perspective view of a transportable
cart showing our new design;

FIG. 2 is a front elevation view thereof;

FIG. 3 is a rear elevation view thereof;

FIG. 4 is a side elevation view thereof, the opposite side
being a mirror image of that shown;

FIG. 5 is a top plan view thereof; and

FIG. 6 is a bottom plan view thereof.
